R. J. Darbon

UNITED STATES PATENT OFFICE.

FRANK W. HALL, OF PORT ARTHUR, TEXAS, ASSIGNOR TO THE TEXAS COMPANY, OF NEW YORK, N. Y., A CORPORATION OF TEXAS.

PROCESS FOR PRODUCING ALUMINUM CHLORIDE.

Application filed March 15, 1920. Serial No. 365,861.

To all whom it may concern:

Be it known that I, FRANK W. HALL, a citizen of the United States, and a resident of Port Arthur, county of Jefferson, and 5 State of Texas, have invented certain new and useful Improvements in Processes for Producing Aluminum Chloride, of which the following is a specification, reference being had to the accompanying drawings, 10 forming a part thereof.

My invention relates to the production of aluminum chloride and particularly to the manufacture of anhydrous aluminum chloride in relatively large quantities.

15 One object of my invention is to manufacture aluminum chloride by means of the reaction obtaining between a suitable aluminum compound, such as alumina, carbon and chlorin at high temperatures and to make 20 the process a continuous one by utilizing the spent ash formed in the reaction to form a seal in the discharge mechanism from the reacting chamber from which the spent materials are continuously removed.

25 Another object of my invention is to provide a process for the aforesaid purpose that shall utilize readily obtainable ingredients, and that shall be particularly adapted for use in the oil industry in producing 30 anhydrous chloride, suitable for use as a catalyst in the treating and decomposition of oils.

Figure 1 is a partially sectional elevation of a retort, together with a suitable furnace and condenser, arranged and adapted for 35 practicing the process of my invention with the exception of the initial steps.

Figure 2 is an elevation of a coking oven in which certain of the materials are prepared in condition to be introduced into the 40 retort of Figure 1.

Figure 3 is a transverse sectional elevation of the coking oven.

Figure 4 is an elevation in detail of the 45 charging mechanism for the retort shown in Figure 1.

Figure 5 is an elevation in detail of the discharging mechanism.

Before describing the process with which 50 my present invention is concerned I will describe the apparatus and then point out the way in which it is used for carrying out my process.

Referring to the drawings: 55 10 is a vertical retort having a chamber or

barrel 11 which is heated by the gases from the furnace 12. The hot gases formed in the combustion chamber 13 of the furnace pass through a flue 14, encircle the retort and escape through a discharge flue 15. Chlorin 60 gas is introduced into the retort through a gas inlet pipe 16.

The retort is provided with a suitable charging mechanism for admitting materials into the retort in a continuous or periodic manner so that the retort may always contain the necessary reaction materials.

As clearly shown in Figure 4 a hopper 17 is provided and is preferably arranged to receive heat in order that the charge may be 70

preheated before it is admitted into the retort. In the mechanism shown the hopper is placed outside the direct current of the furnace gases but is so positioned that it will receive the heat of radiation from the 75 furnace. The materials are admitted into the hopper 17 through the lid 18 and the admission of the charge to the retort is controlled by the bell valve 19 operated by the

rod 20. The valve 19 is more or less cone shaped and contains at its base an extension or flange member 21 having a groove 22 which is adapted to engage the bottom of the hopper 17 when the valve is drawn upward in a closed position. The groove 22 is adapted to contain a powdered or pulverized material such that when the valve is closed a 80

tight seal is made which prevents the escape of vapors and gases from the retort. When using the materials which I commonly employ in my process there are always at least small quantities which become more or less pulverized and which will lodge in the groove 22 permitting the larger particles to readily pass over the flange 21 and into the 90 retort when the valve is opened by moving it downward.

While it is advantageous to preheat the charge in the hopper 17 it is also desirable in order to maintain the valve 19 in proper 100 working condition that this valve should not be subjected to excessive heat. In order to keep the valve in a comparatively cool condition a cooling system is preferably provided. This may be done by constructing 105 the valve operating rod 20 in the form of a pipe containing within it a smaller pipe 23, these pipes terminating within the hollow valve member 19 and the pipe 23 being preferably extended within the cone to a point 110

near its base, as illustrated. One pipe is connected to a suitable source of water, not shown, and the other pipe forms the water outlet thus providing for a circulation of water through the hollow cone. The pipes 20 and 23 may conveniently terminate in a flexible hose, not shown, in order that the pipe 20 may be movable so as to operate the valve 19, the pipes being held in position 10 when the valve is closed in any convenient manner.

The retort has a cylindrical extension or outlet 24 which terminates within a rotary pan 25, as clearly shown in Figure 5. The 15 pan is supported by means of rod 26, journaled at 27 and extending through the pan so as to support the perforated grate 28. The pan is rotated by means of a shaft 29 which carries a pinion 30 which meshes 20 with a gear wheel 31 on the bottom of the pan.

The grate 28 operates to support the material in the retort while it is being subjected to the chlorination treatment allowing the ash or finer particles to drop into the pan 25, thus the ash or spent material is continuously working out of the retort and discharging into the rotating pan where the accumulated ash forms a seal which prevents the exit of the gases and vapors from the retort. The discharge of the ash into the pan is accelerated by means of the scraper 32 which is rigidly secured to the extension 24 and which serves to remove the ash from 30 the mouth of the extension and conduct it into the path of the stationary plow or scraper 33 which is mounted on a bracket or arm 34. The plow 33 is arranged to scrape the ash only to a given depth so that 35 while the excess ash may be pushed over the rim of the pan the ash required for the maintenance of the seal will not be disturbed. In this way the rotation of the pan causes the ash to be continuously discharged from the retort while at the same 40 time a gas-tight seal is maintained in the discharge apparatus by means of the spent ash.

The aluminum chloride vapors generated 50 are conducted by a vapor line 35 to any suitable type of condenser for collecting the product. I prefer to utilize the type of condenser illustrated which embodies features particularly adapted for use in the practice 55 of the herein disclosed continuous process and comprises a plurality of sections 36, 37, 38, 39 having the connections 40, 41, 42. Each of the condenser sections is provided with a scraper 43 in order that the aluminum 60 chloride deposited on the walls of the condenser may be scraped down into the bottom of the sections. In order that the product may be withdrawn without interfering with the continuity of the process and without admitting air to the condenser a num-

ber of hoppers 44, 45, 46, and 47 are preferably provided to receive the aluminum chloride collected in the respective condenser sections. The gates or valves 48 control the outlets from the condenser sections 70 to the hoppers and the outlets of the latter are controlled by the gates or valves 49.

The mixture to be introduced into the retort is first coked in a suitable coking oven, such as that shown in Figures 2 and 3. This 75 structure comprises a furnace 50 having a combustion chamber 51, a flue 52 and an oven pan or receptacle 53 having a top 54 with charging doors 55.

According to my invention I mix a suitable aluminum ore, such as bauxite, (which has first been dried out, if necessary) with a suitable carbon-containing substance. A mixture of bauxite and soft coal with a suitable binder, such as acid sludge or pitch, 80 may be utilized in my process. However, I prefer in the operation of the present process to prepare a coking mixture in accordance with the process described in my co-pending application #S-362,198, filed 90 March 1, 1920. I prefer to employ a single substance capable of furnishing the carbon necessary for the reaction and also capable of acting as a binder for the mixture. This substance may be a liquid at normal temperatures or it may be a semi-solid substance 95 which is rendered liquid by the application of heat. A suitable pitch composed of bottoms from asphalt base oils or other suitable residues made from petroleum or coal-tars may be employed. One of the best materials that I have used for this purpose is acid sludge which is a well known by-product of oil refineries. In any event, according to my invention I utilize either alone or in 100 combination with other carbon-containing materials, a suitable form of carbon in a mixture with a suitable aluminum ore such as bauxite.

When preparing the coking mixture, the 110 aluminum ore is preferably reduced to a powdered condition and is then mixed with the pitch, acid sludge or other carbon-containing material which has been heated, if necessary, resulting in the formation of a liquid 115 mixture containing the aluminum ore in suspension thereby producing a very intimate contact between the aluminum ore and carbon. When a solid carbonaceous substance, such as soft coal is employed the material 120 is first reduced to more or less of a powdered state and then mixed with the aluminum ore and the binder.

In any case when the aluminum ore and 125 carbon-containing materials have been sufficiently mixed the mixture is introduced into the oven 53 and sufficient heat is applied to coke the mass. The pitch, and especially the acid sludge, is an excellent material to use in the preparation of the coking mixture 130

inasmuch as the bauxite or other suitable aluminum ore is held in suspension during the heating and does not settle out at the bottom with the result that when the mass 5 is coked it is a porous substantially uniform product of mixed aluminum ore and carbon which is especially susceptible to the subsequent chlorination treatment.

The retort 11 is charged with the coked 10 mixture and heat is applied by means of the furnace 13. When the coked mixture is at the proper temperature chlorin gas is introduced through the gas inlet 16 and is diffused through the mass reacting therewith 15 to produce aluminum chloride vapors. The aluminum chloride passes through the vapor line 35 into the condenser sections 36, 37, 38 and 39 where it is condensed as a solid anhydrous aluminum chloride. It collects 20 on the walls of the condenser and is scraped off by means of the scraper 43 and from time to time removed into the hoppers.

There is a relatively fine ash formed in the retort which sifts through the grate 28 25 and passes out of the retort through the outlet 24. In order to carry out my process to the best advantage the coked mixture which is introduced into the retort contains an excess of aluminum ore, that is, a somewhat 30 larger proportion of aluminum compound than is theoretically required to carry on the reaction obtaining between aluminum compound, carbon and chlorin. This excess aluminum compound such as alumina 35 insures the production of a fine white ash and facilitates the formation of an ash seal in the retort discharge mechanism. The excess ash is continuously discharged over the rim of the rotating pan by means of the plow 33 while at the same time there is 40 constantly a quantity of ash in the rotating pan to form a gas-tight seal.

The charge within the retort is replenished by a continuous introduction of coked 45 material through any suitable continuous discharging device or if desired the coked mixture after being preheated in the hopper 17 is admitted to the retort from time to time as needed so as to maintain a constant 50 supply of coked mixture in the reaction zone and thus make the process a continuous one.

My invention may, of course, be practiced by any suitable apparatus, that shown and 55 described being merely for purposes of illustration and I intend that only such limitations be imposed as are indicated in the appended claims.

What I claim is:

60 1. The process of making aluminum chloride that consists in charging a coked mixture of an aluminum compound and a reducing agent into a heated retort and maintaining a supply of the coked mixture there- 65 in, chlorinating the mixture, continuously

70 withdrawing the spent material, and withdrawing the aluminum chloride vapors.

2. The process of making aluminum chloride that consists in continuously maintaining a coked mixture of an aluminum compound and carbon in a heated retort, passing chlorin gas through the mixture in the retort, continuously removing the ash from the retort, at the bottom, and drawing off the aluminum chloride vapors produced. 75

3. The process of making aluminum chloride that consists in admitting a coked mixture of aluminum oxide and carbon into a heated retort, passing chlorin gas through the mixture in the retort, adding fresh portions of the coked mixture to constantly maintain a supply in the retort, continuously removing the ash from the retort, and drawing off and condensing the aluminum chloride vapors produced. 80

4. The process of making aluminum chloride that consists in coking a mixture of aluminum compound and a carbon containing substance, introducing the coked mixture into an atmosphere of chlorin at reaction temperatures, continuously maintaining a supply of the coked mixture in the reaction chamber, continuously withdrawing the ash formed from the zone of reaction, causing the ash to form a seal in the discharge outlet of the reaction chamber while continuously discharging the excess ash therefrom, and collecting the aluminum chloride produced. 85

5. The process of making aluminum chloride by means of the reaction obtaining between alumina, carbon and chlorin that consists in introducing into a retort a coked alumina-carbon mixture containing an excess of alumina, reacting chlorin with the mixture to form aluminum chloride vapors and ash, continuously removing the ash from the zone of reaction while maintaining a supply of alumina-carbon coke therein, causing the ash to form a seal in the retort outlet, continuously removing the excess ash therefrom and collecting the aluminum chloride formed. 90

6. The process of making aluminum chloride that consists in constantly maintaining a quantity of alumina-carbon coke in an atmosphere of chlorin at reaction temperatures and continuously removing from the reaction chamber the ash and aluminum chloride formed. 105

7. The process of making aluminum chloride that consists in charging a heated retort with an alumina-carbon coke, continuously passing chlorin into the retort to form aluminum chloride vapors and ash, collecting the ash at the bottom of the retort so as to form a gas-tight seal in the outlet thereof, removing the excess ash therefrom, and condensing the aluminum chloride. 110

8. The process of making aluminum chlo-

- ride by means of the reaction obtaining between alumina, carbon and chlorin that consists in constantly maintaining a quantity of alumina-carbon coke in an atmosphere of chlorin at reaction temperatures, maintaining an excess of alumina in the reaction zone to form a fine ash, causing said ash to accumulate at the base of the retort so as to form a gas-tight seal in the outlet thereof, 10 continuously removing the excess ash and condensing the aluminum chloride.
9. The process of making aluminum chloride by means of the chlorination of an aluminum ore and carbon that consists in introducing a coked mixture of aluminum compound and carbon containing an excess of the aluminum compound, chlorinating the mixture to form aluminum chloride vapors and ash and removing the ash through a self-sealing joint to exclude extraneous gas.
10. In the manufacture of aluminum chloride by means of the reaction obtaining between aluminous and carbonaceous material and chlorin, the step that consists in withdrawing solid products formed in the reaction through a seal formed of said solid products.
11. In the manufacture of aluminum chloride by means of the reaction obtaining between aluminous and carbonaceous material and chlorin, the step that consists in withdrawing ash formed through a self-sealing joint that precludes the escape of interior gases.
12. In the manufacture of aluminum chlo-

ride by means of the reaction obtaining between aluminous material and chlorin in presence of a reducing agent, the step that consists in withdrawing spent solid material from the reaction chamber through an outlet passage arranged and adapted to prevent any substantial interchange of gases between the interior of the chamber and the atmosphere.

13. In the manufacture of aluminum chloride by means of the reaction obtaining between aluminous and carbonaceous material and chlorin, the step that consists in withdrawing ash formed through a passage arranged and adapted to prevent the escape of interior gases.

14. The process of making aluminum chloride that comprises heating aluminous material in the presence of a reducing agent and chlorin and withdrawing ash formed from the reaction chamber while the reaction is underway.

15. The process of manufacturing aluminum chloride that comprises charging aluminous and carbonaceous material into a retort, heating the retort, introducing chlorin thereinto, withdrawing ash formed from the bottom of the retort while the reaction is underway and adding fresh charges of aluminous and carbonaceous material to maintain a supply thereof in the retort.

In witness whereof, I have hereunto set my hand this 18th day of February, 1920.

FRANK W. HALL.
